Primary Examiner — Selina Sikder(74) *Attorney, Agent, or Firm* — HAUPTMAN HAM,
LLP(57) **CLAIM**

The ornamental design for a push-button switch member as shown and described.

DESCRIPTION

FIG. 1 is a front view of a push-button switch member according to a first embodiment of my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a top perspective view thereof;

FIG. 8 is a bottom perspective view thereof; and,

FIG. 9 is a sectional view taken along line 9-9 of FIG. 5.

The dash lines show portions of a push-button switch member that form no part of the claimed design. The dash-dot lines depict the boundaries of the claim and form no part thereof.
